CLAIM

The ornamental design for a combined checkbook and computer therefor, as shown and described.

DESCRIPTION

FIG. 1 is a perspective view of a combined checkbook and computer therefor showing our new design;

FIG. 2 is a top plan view thereof on an enlarged scale;

FIG. 3 is a bottom plan view thereof;

FIG. 4 is a side elevational view thereof;

FIG. 5 is a side elevational view thereof opposite that shown in FIG. 4;

FIG. 6 is an end elevational view thereof; and,

FIG. 7 is an end elevational view thereof opposite that shown in FIG. 6.

The broken lines are shown for illustrative purposes only and form no part of the claimed design.

FIG. 2.

FIG. 3

FIG. 4.

FIG. 5.

FIG. 6.

FIG. 7.
